Assistant Examiner — Ji Sun Yoon

(57) **CLAIM**

The ornamental design for a wine glass chiller, as shown and described.

DESCRIPTION

FIG. 1 is a top perspective view of a wine glass chiller, showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a top perspective view thereof, shown in an environmental use;

FIG. 10 is an exploded perspective view thereof, shown in an environmental use;

FIG. 11 is a top perspective view thereof, shown without the base for clarity of disclosure;

FIG. 12 is a bottom perspective view thereof, shown without the base for clarity of disclosure;

FIG. 13 is a front view thereof, shown without the base for clarity of disclosure;

FIG. 14 is a back view thereof, shown without the base for clarity of disclosure;

FIG. 15 is a left side view thereof, shown without the base for clarity of disclosure;

FIG. 16 is a right side view thereof, shown without the base for clarity of disclosure;

FIG. 17 is a top view thereof, shown without the base for clarity of disclosure;

FIG. 18 is a bottom view thereof, shown without the base for clarity of disclosure;

FIG. 19 is a top perspective view thereof, shown without the body for clarity of disclosure;

FIG. 20 is a bottom perspective view thereof, shown without the body for clarity of disclosure;

FIG. 21 is a front view thereof, shown without the body for clarity of disclosure;

(Continued)

FIG. 22 is a back view thereof, shown without the body for clarity of disclosure;

FIG. 23 is a left side view thereof, shown without the body for clarity of disclosure;

FIG. 24 is a right side view thereof, shown without the body for clarity of disclosure;

FIG. 25 is a top view thereof, shown without the body for clarity of disclosure; and,

FIG. 26 is a bottom view thereof, shown without the body for clarity of disclosure.

The broken lines shown in the drawings depict portions of the wine glass chiller that form no part of the claimed design.
